FLASHING

Abraham S. Weinstein, Allston, Mass.

Application August 18, 1930, Serial No. 476,121
Renewed November 10, 1934

24 Claims. (Cl. 72—127)

The present invention relates, generically, to flashing, and more particularly to that type of flashing commonly known as "through flashing".

Flashing of this character is usually made of sheet copper, and is used in building construction in conjunction with the usual layer of mortar between brick joints, or between brick and stone joints, to stop any seepage of water down through the masonry.

The usual practice is to incorporate a flat sheet of metal, usually copper, into the mortar joint at the desired place. This results in a break in the mortar bond at that joint, as mortar does not satisfactorily adhere to copper. The ordinary type of flashing possesses the further disadvantage of tending to slide out of place along the mortar making it difficult to align the several sheets of the flashing.

Among the objects of the present invention is to provide a new and improved type of flashing so formed that it will obviate the above-enumerated disadvantages of the usual flashing,—in other words, will not cause a break in the mortar bond at the joint where it happens to be embedded, but will instead enhance the effectiveness of such joint. It will further be provided with means to overcome any tendency to move in any direction with respect to the mortar in which it is incorporated.

A further object is to provide a flashing having a simple but effective means thereon for connecting it to and holding it securely against relative movement with respect to an adjacent sheet of flashing.

It is still another object of the present invention to provide a novel and improved flashing having the above-described characteristics, and in addition, possessing all the advantages of the old type flat sheet copper flashing, which is easily and readily joined to other flashings.

These and other objects, which will be apparent to those skilled in the art to which the present invention pertains from a perusal of the detailed description thereof hereinafter given, are attained by the embodiments of the invention hereinafter disclosed, consisting of the construction and novel combination and arrangement of parts fully described below, illustrated in the accompanying sheets of drawings and pointed out in the claims hereunto appended.

In the said drawings,

Fig. 1 represents a partially broken-away plan view of a portion of one form of a strip of flashing embodying the present invention;

Fig. 2 represents a sectional view through a portion of a brick wall, illustrating the said form of flashing inserted between two courses of brick;

Fig. 3 is a sectional view taken through Fig. 2 at line 3—3;

Fig. 4 is a top plan view of a portion of modified form of flashing; and

Fig. 5 is a sectional view through Fig. 4 at line 5—5.

Fig. 6 is an enlarged sectional view along line 6—6 of Fig. 4.

Similar reference numerals indicate similar parts throughout the several views of the drawings.

Reference numeral 10 indicates a portion of a strip of flashing constituting one embodiment of this invention. Strips 10 may be preferably constructed of sheet metal, copper being usually employed. Each strip 10 comprises a main body portion 11, which is coarsely ribbed or corrugated as at 12, and end or flange portions 13 which are finely ribbed or corrugated as at 14.

The coarse corrugations 12 are preferably extended across the body portion 11, as shown, in the form of sinuous curves. These may conveniently be formed by passing the originally flat copper sheet from which the flashing is preferably formed, through suitably formed rollers, or in any other desirable manner. The formation of the coarse corrugations 12 obviously causes a considerable shrinkage in the width of the original copper sheet.

To compensate for this shrinkage in width, it is necessary to corrugate the end or flange portions 13 also. By the use of suitably designed rollers, the fine corrugations 14 may be formed simultaneously with the formation of the other corrugations 12.

Ideally, it is desirable that the flange members 13 be flat, so that they may be easily bent and joined to other flashings. However, by the formation of the fine corrugations 14, the shrinkage in width of the strip is compensated for, and a substantially flat and easily workable flange is obtained. As shown in the drawings, there are three complete corrugations 14 for each coarse corrugation 12.

The corrugations 12 obviously prevent movement of the flashing, relative to a layer of mortar upon which it may be placed, in a direction transversely of said corrugations, and because of the curved or sinuous character thereof, they also prevent movement in a direction longitudinally of the general extent of said corrugations.

Several strips of this form of flashing 10 may be conveniently connected together by merely placing the end ribs or corrugations 12 of one strip over and in coincidence with the end ribs 5 or corrugations 12 of the next adjacent strip. It is obvious that the several strips will thus be held securely against relative movement, transverse or longitudinal, with respect to each other.

If the flashing were constructed merely as has 10 been thus far described, and were inserted into a layer of mortar 15 between two courses of brick 16, such as is shown in Fig. 2, the flashing would be securely held against movement with respect to the mortar in any horizontal direction. However, because of the nonadherence of the mortar to copper, it would be possible to lift the upper course of brick 16 and its subjacent layer of mortar directly off of the flashing strip. In other words, the mortar bond between the 15 two courses of brick would be broken by the insertion therebetween of the strip of flashing.

To obviate this difficulty, the flashing 10 is formed, in addition to the above-described corrugations, with a plurality of hollow frusto-conical protrusions or buttons 17. As is shown 25 in Figs. 1 and 2, the buttons 17 are struck, or otherwise conveniently projected, out from the corrugations 12 in rows and in alternately upwardly and downwardly extended relation.

The hollows of the upwardly extended protrusions or buttons 17 are substantially filled 30 with mortar when the flashing 10 is laid upon the mortar 15, and because of the frusto-conical, or dovetail-like, construction thereof form a mortar lock which prevents the said strip 10 of flashing from being lifted upwardly from the subjacent layer of mortar.

A similar mortar lock joint is formed by the 40 downwardly projecting buttons 17 between the flashing 10 and its subjacent layer of mortar. It is thus seen that instead of breaking the mortar bond, the flashing constituting the present invention enhances this bond by being securely locked to the mortar both above and 45 below it.

Coming now to the modification illustrated in 50 Figs. 4 and 5, this comprises an originally flat sheet 20 of metal, preferably copper. The middle or body portion of this sheet is formed with a plurality of spaced raised portions or areas 21. These, in effect, form a very coarsely corrugated body portion. The raised areas 21 are connected to the body portion 20 by means of divergently inclined walls 22. The formation 55 of the middle corrugated portion causes a shrinkage in the width of the sheet of metal from which the strip of flashing is being formed. To compensate for this shrinkage, the end or flange portions 23 of the flashing are finely corrugated, as shown at 24.

At a plurality of spaced places therealong, the upper and lower portions of walls 22 are projected in any convenient manner in oppositely-extended directions to form a plurality of dovetail-like projections 25, as is clearly illustrated at the right hand end of Fig. 5.

These projections 25 form mortar lock joints, in substantially the same way as do buttons 17 (above-described), and prevent the flashing 70 from breaking the mortar bond at the point where the flashing happens to be embedded.

Adjacent one end thereof each strip of flashing is formed as shown with a slot 26 adapted to receive the flat end 27 of an adjoining strip. 75 The strips are cut at the slotted ends at a point

just beyond a wall 22, and the flat ends 27 are so proportioned that when they are housed in slots 26, end walls 22 of the adjoining strips of flashing are in superposed and locked relation, the locking being effected by the snapping into coincidence of the dovetail projections 25. In this way, an effective joint for connecting two strips of flashing in securely locked relation is provided.

Having described the invention, what is claimed and desired to secure by Letters Patent 10 is:

1. A flashing comprising a strip of sheet metal having a coarsely corrugated body portion and a finely corrugated end portion substantially co-extensive therewith, said strip having means 15 thereon adapted to interlock and key mortar disposed on each side of said strip.

2. A flashing adapted to be embedded in a layer of mortar or the like comprising a strip of sheet metal having a coarsely corrugated middle portion, finely corrugated end or flange portions, and protrusions displaced from the body of said strip and adapted to interlock the mortar on each side of said strip.

3. In combination, a plurality of superposed 25 courses of masonry, a layer of mortar therebetween, a section of sheet metal flashing partially embedded in said mortar and having an exposed portion extending therefrom, said embedded portion comprising a coarsely corrugated portion 30 having a plurality of projections displaced therefrom and adapted to form mortar lock joints, and said exposed portion including a plurality of relatively fine corrugations.

4. In combination with a layer of mortar or 35 like binding material, a strip of flashing thereon, rib-like means on said strip to prevent movement thereof relative to said layer in the direction of one plane, and additional means to prevent movement of said strip in the direction of a 40 plane at right angles to said first-named plane, said additional means being dovetail-shape in cross section.

5. The combination set forth in claim 4, said additional means projecting from said first- 45 named means.

6. In combination with a layer of mortar or like binding material, a strip of flashing thereon, means on said strip to prevent movement thereof relative to said layer in any direction in one 50 plane, and dovetail-like means adapted to prevent movement of said strip in the direction of a plane intersecting said first-named plane, said second named means being displaced from an intermediate portion of said first named means. 55

7. The combination defined in claim 6, said first-named means comprising a plurality of relatively coarse corrugations.

8. The combination defined in claim 6, said first-named means comprising a plurality of sin- 60 uously-extending corrugations.

9. The combination defined in claim 4, said additional means comprising a plurality of hollow frusto-conical buttons.

10. A flashing of the character described comprising a sinuously corrugated body portion, finely corrugated flange-forming portions, and a plurality of hollow frusto-conical buttons displaced from said body portion.

11. The construction defined in claim 10, certain of said buttons being displaced upwardly from said body portion, and others of said buttons being displaced downwardly from said body portion.

12. A flashing comprising a strip of sheet metal having a plurality of spaced areas displaced

therefrom, divergingly inclined walls connecting said displaced areas to the body of said strip, and means projecting from said walls and adapted to form mortar lock joints.

5   13. A flashing of the character described comprising a body portion and finely corrugated end or flange portions, a plurality of spaced displaced portions on said body portion connected to the latter by inclined walls, each of said walls 10 comprising a plurality of dovetail-like projections formed therein.

14. In combination, a pair of flashings each having an inclined wall, a plurality of dovetail-like projections on said walls, said walls being adapted to be arranged in superposed coincidence, whereby the said flashings are joined together against relative movement.

15. A strip of flashing comprising a plurality of inclined walls, each wall having a plurality of means displaced therefrom and adapted to form a mortar lock joint, and a slot on said flashing adapted to receive the flat end of an adjoining strip of flashing.

16. A flashing of the character described comprising a portion adapted to be entirely embedded in a layer of mortar or the like, hollow frusto-conical projections displaced from said portion for interlocking and keying the mortar above and below said portion, and a second portion substantially coextensive with said first portion and adapted to extend from said mortar and for easy connection to other flashing or the like.

17. A sheet metal flashing comprising a body portion and a flange portion, said body portion comprising a plurality of spaced discs raised from said body portion and connected thereto by tapering walls, said flange portion being substantially flat and adapted to be joined to other flashing or the like.

flashing or the like.

40 18. A strip of flashing comprising a relatively coarsely corrugated body portion adapted to be entirely embedded in a layer of mortar or the like, and relatively finely corrugated end or flange portions adapted to extend from said

45 layer for ready connection to other flashing or the like, said coarsely corrugated body portion being of greater vertical extent than said finely corrugated portions, whereby said body portion constitutes pocket means adapted to prevent

50 horizontal displacement of said flashing in any direction relative to said layer.

19. A strip of sheet metal flashing adapted to be embedded in a layer of mortar or the like including a body portion having a plurality of sets of protrusions adapted to prevent movement of said flashing in any direction relative to said

layer, ribs disposed between the several sets of protrusions and adjacent each end of said strip, whereby means is provided for joining contiguous strips of flashing by superposing said end ribs.

20. A flashing comprising a continuous strip of sheet material provided with oppositely disposed overhanging projections and depressions upon opposite faces thereof, each projection and depression embodying therein a side wall extending entirely therearound and offering a resistance against a movement of the flashing within a wall in a plane parallel to the opposite faces of the flashing which will be equal in all directions. 10 15

21. A flashing comprising a continuous strip of sheet material provided with a plurality of overhanging projections and oppositely disposed depressions on a surface thereof, the side wall of said projections and depressions extending entirely therearound, and a plurality of beads extending transversely across said strip. 20

extending transversely across said body portion.

22. A sheet of flashing comprising a transversely corrugated body portion adapted to be entirely embedded in a layer of mortar or the like, a flange portion of single sheet thickness and substantially coextensive with said body portion extending from the latter, whereby said flashing may be readily locked to other flashing or the like, the corrugations of said body portion terminating adjacent said flange portion, whereby pocket means are provided in said body portion for preventing horizontal displacement of said flashing in any direction relative to said layer.

23. A sheet of flashing comprising a body portion adapted to be entirely embedded in a layer of mortar or the like, and a flange portion of single sheet thickness and substantially coextensive with said body portion extending from the latter, whereby said flashing may be readily locked to other flashing or the like; said body portion being provided with a plurality of transversely arranged corrugations terminating adjacent to and merging into said flange portion; said corrugations comprising a wall displaced from said body portion and disposed in a plane substantially parallel to the plane of the latter, and inclined walls connecting said displaced wall with said body portion and adapted to serve as keys for mortar. 40 45 50

24. The construction defined in claim 23, said inclined walls comprising portions disposed in different directions of inclination.

ABRAHAM S. WEINSTEIN.
